UNITED STATES PATENT OFFICE.

CLARENCE R. TEAFORD, OF FARMLAND, INDIANA.

CURTAIN FASTENER FOR AUTOS.

Application filed March 6, 1925. Serial No. 13,517.

This invention relates to curtain fasteners and more particularly to fasteners for automobile curtains. The object of the invention is to provide a simple and efficient device of this character which may be fastened and unfastened from the inside of the car without stretching or tearing the curtains such as frequently occurs by forcing the hands through the openings to fasten the 10 curtain from the outside.

Another object of the invention is to construct a fastener of this character which may be automatically fastened either from the inside or outside and which when fastened will not work loose, and must be manually operated to release the curtain.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within 25 the scope of what is claimed without departing from the spirit of the invention.

In the accompanying drawings:—

Figure 1 represents a front elevation taken from inside the curtain showing this improved fastener applied and in open position to release the button in connection with which it is to be used;

Fig. 2 is a similar view showing the fastener closed and engaged with the button;

Fig. 3 is an elevation taken from outside the curtain with the parts in open position as shown in Fig. 1;

Fig. 4 is a plan or edge view thereof; and

Fig. 5 is a detail sectional view showing 40 the cam shank of the jaw actuating member constituting a part of the invention.

The fastener constituting this invention comprises two substantially heart-shaped plates 1 and 10 designed to be arranged on the outer and inner faces respectively of the curtain C with the slots 2 and 11 thereof registering with each other, the curtain at this point being cut out to permit the button or headed stud 30 to pass into said slot 50 and secured by means presently to be described.

These plates 1 and 10 are shown connected with the curtain C clamped between them by means of bendable prongs 3 carried by the 55 edges of plate 1 and which are extended

through the curtain and clampingly engaged with the plate 10 whereby the plates are securely held in operative position.

Headed studs 14 and 15 project laterally from the lobes 12 and 13 of plate 10 and mounted to slide transversely on these studs are two latch members 16 and 17 here shown made in the form of substantially triangular plates having slots 18 extending transversely across one end to receive the studs on which 65 these plates slide. The inner end 19 of said plates are mounted on the free ends of plate springs 20 and 21 which are fixedly mounted at the apex of the plate 10 as is shown clearly in Fig. 5. These springs have a tendency to 70 move toward each other and consequently normally close the latch members in the position shown in Fig. 2. The corners of the plates 16 and 17 to which the springs are secured are truncated or cut off as shown 75 clearly in Fig. 1, to adapt them to fit against the shank of the curtain button 30 when closed to securely lock the plates in engagement with said button as is shown clearly in Fig. 2.

A rotary cam 22, here shown elliptical in cross section, is mounted between the springs 20 and 21 so that when turned to present its long end to said springs they will be forced apart into the position shown in Fig. 1 to 80 open the latch members. An operating knob 23 is carried by the cam 22 and projects on the inside of the curtain as shown so that this cam may be readily turned for opening the button engaging jaws. Another operating knob 24 is preferably located on the outside of the curtain and also fixed to the cam 22 for operating the jaws on the outside of 85 the car.

From the above description it will be obvious that when this fastener is applied as shown in the drawings the jaws or latch members 16 and 17 may be readily opened by turning the knob 23 to position the cam crosswise between the springs 20 and 21 100 thereby forcing said springs apart and opening the jaws. When this knob is turned in the opposite direction to release the cam from the springs these springs will operate to automatically close the jaws and engage 105 the shank of button 30 which has been entered in the slots 11, said jaws being located on the outer side of said button shank to securely hold it engaged with the fastener.

It will thus be seen that fasteners of this 110

character applied to automobile or other curtains may be readily engaged with the buttons on the bows of the vehicle from the inside and could be detached when desired.

5 By providing the knobs 24 on the outside they may be also removed from the exterior of the car.

In applying the curtains the fasteners are automatically snapped over the shanks of 10 buttons 30 which is accomplished by slipping the fasteners on the button shanks the pressure against latches 16 and 17 causing them to open against the tension of spring arms 20 and 21 and permit said button shanks to 15 move inwardly behind the latches as shown in Fig. 2. To release the buttons the cam is turned to the position shown in Fig. 1 to open the latches 16 and 17.

I claim:—

20 1. A curtain fastener comprising a heart-shaped plate having an open slot between the lobes thereof, latch members mounted to slide transversely on said lobes toward and away from each other, plate springs secured 25 at one end to said latch members and at their other end to the apex of the plate, said

springs being connected to normally move toward each other and an elliptical cam located between said springs and equipped with a knob for turning to force the springs 30 apart when turned with the extreme length between the springs whereby the latches are opened to release the cooperating fastening members, the springs operating to close said latch members when the cam is turned with 35 its shortest dimension between the springs.

2. In a device of the character described, a plate having a slot extending from one edge thereof, latch members having transversely disposed elongated openings, studs 40 extending through the openings and having connection with the plate adjacent to the slot, springs engaging the latch members to normally urge the latch members towards each other, and a cam disposed between the 45 springs for moving the latch members away from each other, and said latch members adapted to hold a stud within the slot.

In testimony that I claim the foregoing as my own, I have hereto affixed my signature.

CLARENCE R. TEAFORD.
